Gorke, Leverkusen-I. G. Werk, Germany, as-
signors to I. G. Farbenindustrie Aktiengesell-
schaft, Frankfort-on-the-Main, Germany

Application December 26, 1934, Serial No. 759,286

8 Claims. (Cl. 204—9)

This invention relates to a process of purifying alkali metal hydroxide solutions from chlorate ions and heavy metal impurities, such as iron, which process consists in subjecting the impure solutions to an electrolytic treatment.

The alkali metal hydroxide solutions obtained by electrolysis almost in every case contain a smaller or greater amount of chlorate and metallic impurities, particularly iron, and therefore are not suitable for many applications.

In accordance with the present invention the chlorate as well as also the heavy metal impurities are eliminated from the alkali metal hydroxide solutions by subjecting the solutions to electrolysis while using iron anodes. Hereby the iron dissolving at the anode reduces the chlorate to chloride. The violet color first beginning at the anode becomes deep blue during the treatment. Then the iron present in the solution, and eventually also other heavy metals, such as copper, are eliminated from the solution by subjecting the alkali metal hydroxide solution to electrolysis while using indifferent anodes, such as nickel, graphite and the like anodes. By this second treatment the heavy metals, iron, copper etc. are deposited upon the cathode. Both processes can be accelerated by applying higher temperatures, say, for instance, temperatures ranging from 80—110° C.

The invention is further illustrated by the following examples without being restricted thereto:

Example 1.—In a vessel containing 5 liters of a 33% caustic soda solution a number of nickel and iron wire nets are arranged parallel to one another and at intervals of about 15 mms. The nickel nets connected with one another form the one, the iron nets the other electrode. The solution is then heated to about 100° C. and a continuous current is passed through the solution whereby the iron nets serve as the anode and the nickel nets as the cathode. The current density amounts to about 10 amperes per square meter of the electrode surface. As soon as the chlorate is reduced the current is reversed so that now the nickel nets serve as the anode and the iron nets as the cathode. The heavy metals are then deposited on the iron cathode whereupon for accelerating the process the current density is increased to 30 to 40 amperes per square meter of electrode surface.

The process is preferably performed in a continuous working manner, for instance, by effecting in one container only the reduction of the chlorate, and in another container the removal

of the heavy metals. Therefore, in the first container cathode and anode are preferably made of iron. The efficiency of the anode gradually slackens, this can however be avoided by reversing the current from time to time, so that 5 the cathodically connected iron sheets become the anode and the anodically connected iron sheets become the cathode.

Instead of the reversed continuous current also an alternating current may be used in the first 10 stage.

Example 2.—In a vessel containing a 50% caustic soda solution a number of perforated iron sheets are arranged parallel to one another at intervals of about 20—30 mms. which serve as 15 cathodes and anodes. The solution is heated to about 110° C. and a continuous current of about 10 amperes per square meter of the electrode surface is passed through. After some time so much of the 50% caustic soda solution is introduced at 20 the one end of the vessel that the solution running off at the other end of the vessel is just free from chlorate. The current is reversed about every 4—6 hours. The solution running off flows into a second vessel wherein a number of iron 25 sheets are arranged as cathodes. Nickel sheets serve as the anodes. Through this vessel parallel to the first vessel a continuous current of about 40 amperes per square meter of the electrode surface is passed which, needless to say, must not 30 be reversed.

The solution flowing off from the second vessel is practically free from chlorate and iron.

We claim:

1. Process of purifying alkali metal hydroxide 35 solutions from chlorate and heavy metal compounds contained therein which comprises subjecting the solutions at first to an electrolytic treatment while using iron anodes and then to a second electrolysis while using indifferent 40 anodes.

2. Process of purifying alkali metal hydroxide 45 solutions from chlorate and heavy metal compounds contained therein which comprises subjecting the solutions at an elevated temperature at first to an electrolytic treatment while using iron anodes and then to a second electrolysis while using indifferent anodes.

3. Process of purifying alkali metal hydroxide 50 solutions from chlorate and heavy metal compounds contained therein which comprises subjecting the solutions in a first stage to an electrolytic treatment while using iron electrodes and reverse the poles from time to time, in a second 55

stage to a second electrolysis while using indifferent anodes.

4. Process of purifying alkali metal hydroxide solutions from chlorate and heavy metal compounds contained therein which comprises subjecting the solutions at an elevated temperature in a first stage to an electrolytic treatment while using iron electrodes and reverse the poles from time to time, in a second stage to a second electrolysis while using indifferent anodes.

5. Process of purifying alkali metal hydroxide solutions from chlorate and heavy metal compounds contained therein which comprises subjecting the solutions at first to an electrolytic treatment at a current density of about 10 amperes per square meter while using iron anodes and then to a second electrolysis at a current density of about 30-40 amperes per square meter while using indifferent anodes.

15 6. Process of purifying alkali metal hydroxide solutions from chlorate and heavy metal compounds contained therein which comprises subjecting the solutions at an elevated temperature at first to an electrolytic treatment at a current density of about 10 amperes per square meter while using iron anodes and then to a second elec-

trolysis at a current density of about 30-40 amperes per square meter while using indifferent anodes.

7. Process of purifying alkali metal hydroxide solutions from chlorate and heavy metal compounds contained therein which comprises subjecting the solutions in a first stage to an electrolytic treatment at a current density of about 10 amperes per square meter while using iron electrodes and reverse the pole from time to time, 10 in a second stage to a second electrolysis at a current density of about 30-40 amperes per square meter while using indifferent anodes.

8. Process of purifying alkali metal hydroxide solutions from chlorate and heavy metal compounds contained therein which comprises subjecting the solutions at an elevated temperature in a first stage to an electrolytic treatment at a current density of about 10 amperes per square meter while using iron electrodes and reverse the 15 poles from time to time, in a second stage to a second electrolysis at a current density of about 30-40 amperes per square meter while using indifferent anodes.
